UNITED STATES PATENT OFFICE

ISAAC N. VAN PELT, OF LAMAR, MISSOURI.

CULTIVATOR.

No. 818,492.

Specification of Letters Patent.

Patented April 24, 1906.

Application filed November 2, 1905. Serial No. 285,628.

To all whom it may concern:

Be it known that I, ISAAC N. VAN PELT, a citizen of the United States, residing at Lamar, in the county of Barton and State of Missouri, have invented a certain new and useful Improvement in Cultivators, of which the following is a specification, reference being had therein to the accompanying drawings.

10 This invention relates to an improvement in cultivators; and the object of the invention is the provision of means whereby the operator may readily control the direction of movement of the cultivator without raising the teeth thereof from out of the ground.

15 A further object of the invention is the provision of an improved frame for the cultivator, whereby great rigidity will be obtained, together with simplicity of construction.

20 Other objects of the invention will be apparent from the description hereinafter when read in connection with the accompanying drawings, forming a part hereof, wherein a 25 preferable embodiment of my invention is shown and wherein like letters of reference refer to similar parts in the several views.

25 In the drawings, Figure 1 is a perspective view of my improved cultivator. Fig. 2 is a 30 horizontal section of my improved cultivator with parts broken away; and Fig. 3 is a longitudinal section thereof, parts being broken away.

35 Referring now more particularly to the drawings, A A designate the cultivator-beams, the rear ends of which are substantially parallel and the forward ends of which converge to the head-block B, to which they are rigidly secured in any suitable manner.

40 The beams A A are preferably formed of a single piece of strap metal, which is bent at its central portion to partially encircle the head-block B, said head-block being provided with a channeled portion b, adapted to receive the strap metal constituting the beams A A.

45 The beams A A are connected and strengthened by means of the trussed braces C C. The braces C C are preferably formed of a single piece of strap metal which is folded at its central portion, so as to partially encircle the head-block B and to lie within the channeled portion b thereof underneath the strap which constitutes the beams A A. The

55 forward ends of the beams A A and the braces C C are preferably connected to the head-block B by bolts or screws, which extend therethrough and into the body of said head-block. The braces C C extend rearwardly from the head-block B, and are then bent outwardly, so that the free ends thereof 60 will lie in proximity to the free ends of the beams A A. The parallel portions of the braces C C are connected by means of a block D, fitting therebetween, said block being provided along its sides with channeled portions 65 d for the reception of said braces. A bolt E extends transversely through the braces and blocks and serves to rigidly connect the parts.

70 F F designate bearing-blocks which are provided with vertically-disposed apertures f, extending vertically therethrough, and with the laterally-extending portions f'. The laterally-extending portions f' of the bearing-blocks F F extend between the adjacent ends 75 of the beams A A and the braces B B and are secured therein by means of bolts which pass through the ends of the beams and braces and the interposed projections. From this construction it will be apparent that when the bearing-blocks become worn or broken 80 they can readily be detached and replaced with new ones.

85 G G designate cultivator-shovels of any type which are provided with stems g g', which are adapted to fit in the apertures f of the bearing-blocks F F and which are adjustably secured therein by means of set-screws f'', secured in the sides of the bearing-blocks and adapted to impinge against said stems. A similar cultivator-shovel G' is 90 mounted in an aperture D', formed in the block D, said shovel being adjustably secured by a set-screw d', secured in a boss d'', surrounding the aperture D' and adapted to impinge against the stem of the shovel.

95 H H designate bearing-blocks which are removably secured to the beams A A, intermediate the ends thereof, by means of bolts h or in any other suitable manner. The bearing-blocks H H are provided with suitable apertures extending vertically therethrough, in which are adapted to loosely fit the stems i of the cutters I I. When the cutters I I are secured in the bearing-blocks H H, the upper portions of the stems i thereof project beyond said bearing-blocks, and to the project-

ing portions of the stems are rigidly secured in any suitable manner the inwardly-extending arms K K, which are provided at their free ends with the upturned portions k, for 5 the purpose hereinafter more particularly set forth. The cutters I I are in the form of runners and have their forward ends rounded, so as to readily ride over any obstructions which they are incapable of cutting through.

10 L designates a cutter similar in form to the cutters I I, the stem l of which is journaled in a vertically-disposed aperture b' in the bearing-block B, so as to turn freely therein, said cutter being held therein by a 15 cotter-pin or other suitable fastening means.

M designates an arm which is pivotally connected at its central portion to the rear end of the block D, preferably by means of a stem m, which extends downwardly therefrom and fits loosely in an aperture in said block. The ends of the arm M are provided with bifurcated portions m', which loosely embrace the upturned portions k of the arms K K, secured to the cutters I I. The arm M 25 is provided with the upwardly and rearwardly extending portions m², to which are secured in any suitable manner the handles N N. The arm M is also provided with the forwardly-extending projection m³, which 30 when the arm M is moved travels over the face of the block D between the lugs d³ formed thereon, said lugs serving to limit the movement of the arm in either direction.

O designates a draft-rod the rear end of 35 which is provided with an aperture o, adapted to engage a hook D² on the forward portion of the block D, and the forward portion of which extends between two upwardly-extending curved plates P P, which are secured 40 in any suitable manner to the forward portion of the cultivator. The plates P P are provided with a plurality of pairs of aligned apertures p, and the draft-rod O is provided with a single aperture therein, which is designed to be brought into alignment with any 45 pair of the apertures p, according as it is desired to adjust the position of the draft-rod, a pin p' being utilized to hold said draft-rod in its various positions of adjustment. From 50 this construction it will be apparent that the draft is from the block D, which is positioned in substantially the center of the cultivator, and that the shovels will therefore be forced into engagement with the ground, the depth of cut being regulated by adjusting the draft-rod O between the plates P P.

In use when for any reason the operator desires to deflect the course of the cultivator he has only to shift the handles N N, which 60 will turn the arm M, which through its connection with the arms K K will turn the cutters I I in the bearing-blocks H H, which will effect the desired shifting of the course of the

cultivator without raising the shovels thereof from out of the ground.

I do not desire to limit myself to the precise form and construction shown in the drawings, as it is obvious that many minor changes might be made thereto without departing from the spirit of the invention.

What I claim, and desire to secure by Letters Patent, is—

1. A cultivator-frame comprising diverging beams, and truss-braces secured to the inner sides of said beams and extending from the front to the rear ends thereof, adjacent portions of said braces intermediate the ends thereof being rigidly connected to each other.

2. A cultivator-frame comprising diverging beams, truss-braces secured to the inner sides of said beams and extending from the front to the rear ends thereof, and a block interposed between and rigidly connected to said braces intermediate the ends thereof.

3. A cultivator-frame comprising a piece 85 of metal folded upon itself to form divergent beams, and bowed braces secured to the inner sides of said beams, adjacent portions of said braces intermediate the ends thereof being rigidly connected to each other.

4. A cultivator-frame comprising a piece of metal folded upon itself to form divergent beams, a second piece of metal folded upon itself and secured at its bend and ends to the inner side of the piece of metal forming the 95 beams, the portions of said second piece intermediate its bend and ends being bent inwardly and rigidly connected to each other.

5. A cultivator-frame comprising diverging beams, truss-braces secured to the inner 100 sides of said beams and extending from the front to the rear ends thereof, and shovel bearing blocks removably secured between the adjacent ends of the beams and braces.

6. In a cultivator, a frame, a runner-like 105 cutter journaled in the forward portion thereof, a pair of runner-like cutters journaled in the sides of said frame, a handle pivoted upon said frame and a connection between said handle and the cutters journaled in the sides 110 of said frame.

7. In a cultivator, a frame having a plurality of shovels secured thereto, a pair of cutters journaled in the sides of said frame, inwardly-extending arms secured to said 115 cutters, a cross-bar pivotally secured to the frame and having its ends loosely connected with the free ends of said inwardly-extending arms, and a handle secured to said cross-bar.

8. In a cultivator, a frame having a plurality of shovels secured thereto, a pair of cutters journaled in the sides of said frame, inwardly-extending arms secured to the journals of said cutters and terminating in upturned portions, a cross-bar pivotally se 125

cured to the frame and provided at its ends with bifurcated portions adapted to loosely embrace the upturned portions of the inwardly-extending arms, and a handle secured 5 to said cross-bar.

9. A cultivator-frame comprising diverging beams, truss-braces secured to the inner sides of said beams and extending from the front to the rear end thereof, a block inter-

posed between and rigidly connected to said 10 braces intermediate the ends thereof, and a draft-rod pivotally connected to said block.

In testimony whereof I affix my signature in presence of two witnesses.

ISAAC N. VAN PELT.
